VARIABLE INDUCTOR

Ralph M. Heintz, Palo Alto, Calif., assignor to
Heintz & Kaufman, Ltd., San Francisco, Calif.,
a corporation of Nevada

Application April 17, 1934, Serial No. 726,938

6 Claims. (CL. 171—242)

My invention relates to variable inductors adapted for use in radio transmitting or receiving apparatus.

Among the objects of my invention are: to provide a variable inductor having a minimum of movable current carrying parts; to provide a variable inductor in which there is no dead ends; to provide a variable inductor wherein the overall resistance may be maintained constant; to provide a variable inductor having fewer relatively movable contacting parts; to dispense with the use of coiled pigtails, in the construction of variable inductors, whose inductance varies for different adjustments of the inductor and which, due to frequent flexing are liable to break; to provide a variable inductor in which the inductor itself is non-rotatable; and to provide an improved construction and a more efficient method for varying the inductance of coils.

Other objects of my invention will be apparent or will be specifically pointed out in the description forming a part of this specification, but I do not limit myself to the embodiment of the invention herein described, as various forms may be adopted within the scope of the claims.

Referring to the drawing:

Figure 1 is a sectional elevation of apparatus embodying my invention.

Figure 2 is a fragmental cross sectional view of the inductor. The plane in which the view is taken is indicated by the line 2—2 of Figure 1.

Figure 3 is a diagrammatic view of a typical circuit incorporating the variable inductor of my invention.

In broad terms, my invention comprises an inductor having a plurality of helically disposed electrically conductive turns, and provided with means for supporting it in a fixed position. An electrically conductive guide is provided, disposed adjacent to, and preferably coaxially with, the inductor, said guide having threads thereon which correspond in pitch with the pitch of the turns of the inductor. A resilient conductive link, having one end thereof engaged in a thread of the guide, and the other end thereof in slidable contact with a turn of the inductor, is provided for electrically connecting the two elements; and means are provided for rotating the link about the inductor to cause the end of the link contacting the turn thereof to follow a helical path corresponding with the helix of the turns thereof.

Inductors used in the tuned circuits of high frequency radio transmitters and receivers are generally provided with vernier mechanisms whereby the number of turns of the inductance

in the circuit, or the location of a tap, may be varied. Heretofore it has been the practice to provide a rotatable inductor, having the desired number of helically disposed turns, and provided with a lead screw which permitted the inductor to be advanced past a fixed contact, a distance corresponding with the lead of the helix of the inductor for each revolution thereof.

It is obvious that, due to the combined rotary and axial movement of the inductor, coiled pigtails, or collector rings and brushes, must necessarily be used to permit connection of the inductor with other fixed parts of the apparatus. The inclusion of these pigtails in low frequency circuits, where the inductor is provided with a large number of turns, is not detrimental, but in high frequency apparatus where the inductor has only a few turns, the effect of the pigtails is quite pronounced in varying the overall inductance of the coil between terminals, due to vibration which changes the inductance of the pigtails and due to the erratic behavior of the pigtail in not returning to the same value of inductance for successive settings of the inductor proper. It will be seen, therefore, that the use of an indicating device, such as a dial, with an inductor of this character is impractical due to the fact that the dial would not give a true evaluation of the setting of the inductor. Furthermore, the inductance of the connections may possibly be greater than the inductance of the coil.

I have provided a variable inductor in which pigtails, or like flexible means for connecting the inductor to fixed parts of the apparatus, are eliminated, and one which permits the use of a dial therewith which will give a true indication of the value of inductance included in a circuit.

In greater detail, the variable inductor of my invention preferably comprises a cylindrical insulating form 2 having a helical groove 3 formed thereon for increasing the electrical leakage distance between the turns of an inductance 4 disposed thereon. The form 2 is provided with a closed end 6 having a metallic bushing 7 mounted thereon which is adapted to receive the reduced end 8 of a cylindrical stud 9. A nut 11 is provided, threaded on the stud end 8, for the purpose of securing the form 2 to the stud, and to provide means for connecting the stud with one end of the inductance 4, through the medium of a lead 12. A lead 13 is secured to the other end of the inductance to which other parts of the transmitting or receiving apparatus may be connected. The stud 9 is provided with a threaded end 14 which is screwed into a suitable fixed member, 55

which may be, for example, the panel 16 of the apparatus.

An insulating disk 17 is provided having a bushing 18 which functions, when the end 14 of the stud is screwed into the panel 16, to clamp the disk between the panel and the shoulder of the bushing. The disk is adapted to support a conductive tubular guide 18 having threads 19 formed thereon which correspond in pitch with the pitch of the turns of the inductance 4. A circumferential flange 20 is provided to which the outer edge of the disk is secured. A bent resilient conductive link 21 is provided having at one end thereof a straight portion 22 which is adapted to bear against adjacent ridges 23 of the threads 19 and which is also provided with a pin 24 on which a roller 25, spaced slightly from the bottom of the threads and adapted to roll on the side walls thereof, is journaled. The other end of the link 21 is provided with an inturned portion 27 contacting the inductance 4, the edge of which is curved to conform with the periphery of the inductance. This link serves to electrically connect the inductance and the guide 18, the latter being provided with a terminal 28, the lead 29 from which may be connected with other parts of the apparatus.

The close proximity of the short circuited loop, created by the tubular guide 18, to the inductance 4 would not materially affect the inductance when the latter is used in receiving circuits; however, when it is used in transmitting circuits the eddy current losses caused thereby would be considerable. To eliminate this difficulty I prefer to provide the guide 18 with two or more slots 30 which extend from the edge of the guide to points adjacent the flange 20. Thus the flange is the closest closed loop to the inductance field and it is spaced therefrom a distance which will not permit any appreciable coupling between the two parts. The purpose of the plurality of slots in the guide is to preclude any possibility of the roller 25 bridging the slot and short circuiting the loop formed by the guide if but one slot was provided.

Means are provided for rotating the link about the inductance so as to vary the value of the latter. Rotatably mounted on the stud 8 is a sleeve 31 which has, at one end thereof, a flange 32 to which an insulating arm 33 may be connected by means of the screw 34. The arm is provided with a hollow guide block 35 secured thereto, through which the link 21 passes. The bent portion 37 of the link is adapted to bear 55 against the inner face of the guide block so as to compress the link and cause the ends thereof to press against the guide 18 and the turn of inductance with which it happens to be in contact. The other end of the sleeve 31 is provided with a gear 38 and a pinion 39 carried by a shaft 41, journaled in the panel 16, meshes therewith. Indicating means such as a dial 42 may be secured to the end of the shaft 41.

In operation, the dial 42 is turned, which also 65 rotates the pinion 39. This rotation is imparted to the sleeve 31, through the gear 38, and consequently the arm 33, guide block 35 and the link 21 are rotated together. As the link 21 rotates, the roller 25 will follow the thread 19 with the result that the link is advanced longitudinally at each revolution a distance corresponding with the pitch of the thread, which in this case corresponds with the pitch of the helix of the inductance. By continued rotation of the dial 70 75 42, the portion 27 of the link is caused to follow

the turns of the inductance, in contact therewith, from one end thereof to the other. It is understood that stops, not shown, may be provided either on the inductance or on the guide 18 for limiting the travel of the link.

Figure 3 illustrates a typical circuit using the variable inductor of my invention. This may be considered as a portion of a radio transmitter in which the vacuum tube 43 represents the output tube. The inductor 4 is shown as being shunted across the anode 44 and ground 46 to which the cathode 47 is connected by the lead 48. A variable tuning condenser 49 is shunted across the inductance and the guide 18 is shown as being connected with the antenna 51. Tuning may be accomplished either by varying the condenser 49, or the inductor 4, or both. The circuit may be read as a receiving circuit by considering that the inductor is connected to the grid 52 and that the anode 44 is connected to the radio frequency 20 amplifier of the receiver.

In reiteration, the variable inductor just described possesses marked superiority over the types of variable inductors in present use, by reason of the fewer number of relatively movable 25 current carrying parts contained therein; by reason of the absence of coiled pigtail with their attendant undesirable features, and by virtue of its sturdier and simplified mechanical construction.

It will be understood that the proportions of the mechanism shown in the drawing were chosen for illustrative purposes, and that these proportions, such as the diameter, number of turns, and length of the inductance, and the 35 sizes of other parts of the apparatus, may be varied within wide limits without departing from the spirit of the invention.

I claim:

1. A variable inductor comprising a fixed helical inductance, a fixed coaxial guide spaced axially from said inductance and having threads thereon corresponding in pitch to the turns of said helix, a contact link disposed parallel with the axes of the inductance and the guide and having one end touching said inductance and the other end entering said threads, and means for rotating said link around said inductance and guide.

2. A variable inductor comprising a fixed helical inductance, a fixed conductive guide cylinder having external threads thereon corresponding in pitch with the turns of said inductance, said guide cylinder being substantially of the same diameter as said inductance and mounted coaxially therewith and spaced apart therefrom, a flexible contact link having one end in contact with a turn of said helical inductance and the other end entering said threads, and means rotating around the common axis for directing 60 said link around said guide and said inductance.

3. In combination with a support, a stud fastened to said support, a fixed conductive drum fastened to said stud by an insulating member, said drum having guide threads cut on the external surface thereof, a fixed insulating frame fastened to said stud of the same diameter as said drum, and coaxial therewith, said drum and said frame being spaced apart, a helix mounted on said frame having the same pitch as the 70 threads on said drum, a sleeve mounted on said stud between said drums and said frame, an arm on said sleeve extending radially between said drum and said frame, a link channel in said arm, a spring link passing freely through said channel 75

having one end contacting a turn of said helix and the other end engaging said threads, said link being deformed by said channel to exert pressure on said threads and said turn, and means for rotating said sleeve.

4. A variable inductor comprising a fixed helical inductance, a fixed coaxial guide spaced apart from said inductance and having threads thereon corresponding in pitch with the turns of said inductance, a contact link having one end thereof in contact with a turn of said inductance and the other end thereof in engagement with a thread of said guide, and means movably connected with said link between the point of contact thereof with said inductance and the point of engagement thereof with said guide for moving said link about said inductance.

5. A variable inductor comprising a fixed helical inductance, an arm having a sleeve thereon mounted for rotary movement about the axis of said inductance, means for rotating said arm and sleeve, a contact link slidably positioned in

said sleeve and having one end thereof in contact with a turn of said inductance, said link lying in a position in axial parallelism with the axis of said inductance, and means connected to the opposite end of said link for advancing, 5 when said arm and sleeve are rotated, the end of said link in contact with said inductance, about said inductance in contact therewith.

6. A variable inductor comprising a fixed helical inductance, a fixed cylindrical guide disposed 10 in axial alignment with said inductance and spaced axially therefrom, said guide comprising a plurality of arcuate radially disposed spaced sections, said sections each having co-extensive portions of a screw thread formed thereon corresponding in pitch with the pitch of the turns of said inductance, a contact link having one end thereof engaging a turn of said inductance and the other end thereof in engagement with said 15 screw thread, and means for rotating said contact link about said inductance. 20
